(57) **CLAIM**

We claim the ornamental design for a vending machine door, as shown and described.

DESCRIPTION

FIG. 1 is a top front left side perspective view of a vending machine door showing our new design;

FIG. 2 is a right side elevational view thereof;

FIG. 3 is a left side elevational view thereof;

FIG. 4 is a front elevational view thereof;

FIG. 5 is a top plan view thereof;

FIG. 6 is a top front left side perspective view of a second embodiment of a vending machine door showing our new design;

FIG. 7 is a right side elevational view thereof;

FIG. 8 is a left side elevational view thereof;

FIG. 9 is a front elevational view thereof;

FIG. 10 is a top plan view thereof;

FIG. 11 is a top front left side perspective view of a third embodiment of a vending machine door showing our new design;

FIG. 12 is a right side elevational view thereof;

FIG. 13 is a left side elevational view thereof;

FIG. 14 is a front elevational view thereof; and,

FIG. 15 is a top plan view thereof.

The broken lines in the drawings represent unclaimed environmental subject matter.
